EASEL FRAME

William J. Crosby, Waterbury, Conn.

Application October 30, 1945, Serial No. 625,490

4 Claims. (Cl. 248—37)

1
This invention relates to frames for photographs, mirrors and the like, and aims to provide an improved easel frame.

I have discovered that an easel frame for photographs, mirrors and the like, which is both durable and attractive but inexpensive, may be constructed principally from molded materials such as the synthetic resins which are plastic when heated but set to a hard and rigid state when cooled. Only three different parts need be utilized in the construction of the frame which I have invented. Two of those parts, the panel which holds the photograph or mirror and the leg which supports the panel in upright position, are molded from plastic material. The third part is an ordinary flat steel spring which holds the panel and leg in assembled condition with the leg pivoted to the panel, and also serves as a brake against movement of the leg with respect to the panel.

In accordance with my invention, an easel frame is constructed from a panel and a leg attached to the rear of the panel for pivotal movement through a pair of lugs. The lugs are provided with bearings for journals projecting from opposite sides of the leg. The lugs are provided also with channels communicating with the bearings and the journals are adapted to slide along those channels. A resilient member is provided to seat the journals in the bearings.

A specific embodiment of the easel frame which I have invented, in the form which I now prefer, is illustrated in the accompanying drawings in which:

Fig. 1 is a rear elevation of the easel frame;

Fig. 2 is a side elevation broken away in part to show the connection between the panel and the leg;

Fig. 3 is a fragmentary section illustrating the assembly of the leg and the panel;

Fig. 4 is a fragmentary section along the lines 4—4 of Fig. 1;

Fig. 5 is a front elevation of the portion of the panel to which the leg is attached;

Fig. 6 is a fragmentary section illustrating the mode of assembling a modified form of frame; and

Fig. 7 is a fragmentary section illustrating the leg and panel of Fig. 6 in assembled position.

The frame illustrated in Figs. 1—5 inclusive, includes a molded plastic panel 10 which may be supported in upright position by a molded plastic leg 11. The front of panel 10 has inturned flanges 12 extending along its edges to hold in place the photograph 14 and sheet of glass 15. A

2
pair of lugs 16 project from the rear of panel 10 and provide a connection between that panel and the leg 11. The leg 11 has a polygonal head 18 with a pair of journals 19 projecting from opposite sides. An opening is left in the panel 10 between the lugs 16 and a channel 20 extends along the inner face of each lug 16 from the front edge of that opening to bearings 21 for the journals 19.

10
The panel 10 and leg 11 are assembled by thrusting the lower end of leg 11 through the opening in panel 10 between lugs 16 in the direction illustrated by the arrow in broken lines in Fig. 3. The journals 19 are adapted to slide along the channels 20 until they reach their bearings 21. A flat steel spring 22 is then slid into position between lugs 16 so that its ends abut against shoulders 23 and it presses against the head 18 to hold the journals 19 in their bearings 21.

20
It will be noted that the head 18 of leg 11 has a series of flat faces 24. The resilient spring 22 is adapted to exert a pressure against one of the faces 24. This not only seats the journals 19 in their bearings 21 but also provides a braking action which prevents journals 19 from turning in their bearings 21 so easily that leg 11 will not support the panel 10 in upright position.

The frame illustrated in Figs. 6 and 7 includes a molded panel 27 which, like the panel 10, has inturned flanges 28 extending along its front edges and a molded leg 29 which, like the leg 11, has a polygonal head 30 from which journals 31 project. A pair of lugs 32 project from the rear of panel 27 and contain bearings 33 for journals 31. The inner face of each lug 32 contains a channel 34 shaped like an inverted L with the shorter leg terminating at bearing 33.

The frame illustrated in Figs. 6 and 7 is assembled by sliding the journals 31 along channels 34 as illustrated by the arrow in Fig. 6 until those journals are seated in their bearings 33. The journals 31 are held in their bearings 33 by a flat spring 34 similar to spring 22.

40
The panels 10 and 27 and the legs 11 and 29 may each be formed completely in a mold. Their assembly is a relatively easy operation and consequently the completed frame may be manufactured at small cost.

50
It is to be understood that modifications may be made in the specific embodiment of my invention which I have described without departing from my invention as it is defined in the appended claims.

What I claim is:

55
1. An easel frame comprising a panel having an

opening therein, a pair of lugs projecting from the rear of the panel on either side of said opening, each of said lugs having a bearing and a channel leading from an edge of said opening to the bearing, a leg, journals projecting from opposite sides of the leg and adapted to slide along said channels and to rotate in said bearings, and a resilient member adapted to seat said journals in the bearings.

2. An easel frame comprising a panel having a pair of integral lugs projecting from its rear, each of said lugs having a bearing and a channel leading from an edge of said lug to the bearing, a leg, journals projecting from opposite sides of the leg and adapted to slide along said channels and to rotate in said bearings, and a resilient member adapted to seat said journals in the bearings.

3. An easel frame comprising a panel having a pair of integral lugs projecting from its rear, each of said lugs having a bearing and an L-shaped channel leading from an edge of said lug to the bearing, a leg, journals projecting from opposite sides of the leg and adapted to slide along said channels and to rotate in said bearings, and a resilient member adapted to seat said journals in the bearings.

4. An easel frame comprising a panel having a pair of integral lugs projecting from its rear, each of said lugs having a bearing and a channel leading from its edge to the bearing, a leg having a polygonal head, journals projecting from opposite sides of the head and adapted to slide along said channels and to rotate in said bearings, said head having flat faces parallel with said journals, and a resilient member adapted to exert pressure on one of said faces to seat the journals in the bearings and provide a brake against free rotation of the journals in the bearings.

WILLIAM J. CROSBY.
